UNITED STATES PATENT OFFICE.

ELBERT R. DERRY, OF LEADVILLE, COLORADO.

PRESS.

No. 847,167.

Specification of Letters Patent.

Patented March 12, 1907.

Application filed January 4, 1907. Serial No. 350,710.

To all whom it may concern:

Be it known that I, ELBERT R. DERRY, a citizen of the United States, and a resident of Leadville, in the county of Lake and State 5 of Colorado, have invented a new and Improved Press, of which the following is a full, clear, and exact description.

This invention is an improved press for punching, cutting, and shaping metal or 10 other materials, relating more especially to such devices as are operated by a hand-lever, and in which the operating-tool is struck a blow with a hammer or other device to perform the required operation.

15 The object of the invention primarily is the production of a simple and effective press in which both the movable and stationary tools or dies may be readily changed to suit the character of the work required, also providing for automatically locking the movable 20 tool on grasping the hand-lever employed in reciprocating it.

Reference is to be had to the accompanying drawings, forming a part of this specification, in which similar characters of reference 25 indicate corresponding parts in all the figures.

Figure 1 is a side elevation of my improved press, partly in section, and showing a punch and a die in position therein. Fig. 2 is a plan 30 view of the same. Fig. 3 is a perspective view of a cutting-tool which may be substituted for the punch shown in Fig. 1. Fig. 4 is a perspective view of the female punching-die, and Fig. 5 is a perspective view of a 35 blank die used in connection with the cutting-tool of Fig. 3.

The invention comprises a base 1, preferably of circular shape, as shown, with an opening 2, passing vertically through the 40 center thereof, said opening being counter-bored at its upper end to provide an enlarged recess for receiving an interchangeable and stationary die 3, the preferred form of the latter being in the nature of a disk having a conical bottom face 4, conforming to the seat in the base 1.

The base 1 is extended at the rear side, where it is provided with an upwardly-projecting portion or post 5, providing means 45 for pivotally connecting a hand-lever 6, the latter being constructed with an inclined inner end 7, which is bifurcated at its extremity for embracing each side of the post 5 and pivotally connected therewith by a cross-pin 55 8. The lever 6 has an opening passing verti-

cally through it over the center of the base, which is preferably square in cross-section for receiving the shank of a cutting, punching, or shaping tool 9, said tool having an enlarged head 10 at its upper end acting as a 60 stop to limit its further inward movement when a recess 11 in the shank thereof aligns with a locking-bolt, hereinafter described. The head 10 also provides means for striking the tool with a hammer or other device when 65 the tool has been lowered by the lever in contact with the work. The outer end of the lever 6 is formed with the usual handhold 12 and with a downwardly-extending ear 13 adjacent thereto, to which is pivoted at 14 a 70 bell-crank lever 15, the outer arm of the latter being formed with a rounded enlargement 16, arranged under the handhold 12 and providing a finger-grip for the same when the lever 6 is depressed. 75

Projecting from the under face of the lever 6, adjacent to the tool-opening, are lugs 17, having alining openings in which is slidably mounted a locking-bolt 18, the latter having an extension 19, pivotally connected to the 80 short arm of the bell-crank lever 15 at a point 20. A spring 21, secured to the enlargement 16 of the bell-crank lever 15, presses on the under face of the handhold 12 and normally retains the locking-bolt 18 85 withdrawn from the tool 9, as illustrated in Fig. 1. However, by grasping the handhold 12, with the fingers passing underneath the finger-grip and drawing them together preparatory to reciprocating the tool 9 the locking-bolt, through the action of the intermediary connection, will be forced into the alining recess 11 in the tool-shank, thus securely locking the tool to the lever. 90

In Fig. 3 I have shown a modified form of 95 tool 9^a, which may be substituted for that shown in the press, said tool having a head 10 and a recess 11, the same as those provided in the punch, differing only in that the latter tool is constructed with a chisel cutting edge. 100

In Figs. 4 and 5 are shown female stationary dies 3^a and 3^b, respectively, the former being constructed with the central punching-opening of circular shape and the latter having its operating-face blank. 105

It is obvious that both the movable tool or die and the immovable die may be variously modified to suit the character of the work required, also changes made in the construc- 110

tion of my improved press falling within the scope of the annexed claims.

Having thus described my invention, I claim as new and desire to secure by Letters Patent—

- 5 1. A press comprising a hand-lever having a handhold at the outer end thereof, said lever having means for receiving a tool, and means operable at the handhold of the lever 10 for locking the tool and lever together.
- 15 2. A press comprising a hand-lever having a handhold at the outer end thereof, said lever having means for receiving a tool, and a finger-grip pivotally connected to the lever adjacent to said handhold operable to lock the lever and tool together.
- 20 3. A press comprising a base, a hand-lever pivotally connected with the base having a handhold at the outer end thereof, and means 25 opposed to said handhold operable to lock a tool to the lever.
4. A press comprising a base, a lever pivotally connected with the base having a vertical opening formed therein over the center of the base for receiving a tool, a locking-bolt slidably mounted on the lever, and means operable to project the bolt to lock the tool and lever together.
- 30 5. A press comprising a base having a recess therein forming a seat for a stationary die, a lever pivotally connected with the base having a vertical opening therein arranged over said die, a locking-bolt slidably mount-

ed on the lever, and a finger-grip pivoted to the lever and connected with the locking-bolt 35 operable to project said bolt in said opening, for the purpose described.

6. A press comprising a base having a recess formed therein, a die seated in said recess, a lever pivotally connected with the 40 base having an opening passing therethrough over the die, a tool constructed with a head and with a recess in the shank thereof passing through said opening, a locking-bolt slidable on the lever in alignment with the recess in 45 the shank of the tool, and a finger-grip pivotally connected to the lever operating to project said bolt into the recess of the tool to lock the tool and lever together.

7. A press comprising a base, a lever pivotally connected therewith having a vertical opening passing therethrough and a handhold at its outer end, a locking-bolt slidably mounted underneath the lever, a bell-crank lever pivotally connected with the locking-bolt, a finger-grip carried by the bell-crank lever opposed to said handhold and operating to project the bolt into said opening, and means for withdrawing said bolt.

In testimony whereof I have signed my 60 name to this specification in the presence of two subscribing witnesses.

ELBERT R. DERRY.
